(57) **CLAIM**

The ornamental design for a lamp, as shown and described.

DESCRIPTION

FIG. 1 is a top view of a lamp, showing my new design;

FIG. 2 is a side view thereof;

FIG. 3 is a side view thereof;

FIG. 4 is a side view thereof;

FIG. 5 is a bottom view thereof;

FIG. 6 is a side perspective view thereof;

FIG. 7 is a side perspective view thereof;

FIG. 8 is a bottom perspective view of a second embodiment that is otherwise identical to the embodiment of FIGS. 1-7, with the only difference being the depiction of broken lines on the bottom surface of the light; and,

FIG. 9 is a bottom perspective view of a third embodiment that is otherwise identical to the embodiment of FIGS. 1-7, with the only difference being the depiction of broken lines on the bottom surface of the light.

The broken lines in the drawings depict portions of the lamp that form no part of the claimed design.

1 Claim, 9 Drawing Sheets
